UNITED STATES PATENT OFFICE.

ULRICH WILCK, OF ESSEN-ON-THE-RUHR, GERMANY, ASSIGNOR TO FRIED. KRUPP AKTIENGESELLSCHAFT, OF ESSEN-ON-THE-RUHR, GERMANY.

FUSE AND ADJUSTING-KEY THEREFOR.

1,028,924.

Specification of Letters Patent.

Patented June 11, 1912.

Application filed April 4, 1908. Serial No. 425,157.

To all whom it may concern:

Be it known that I, ULRICH WILCK, a subject of the Emperor of Germany, and a resident of Essen-on-the-Ruhr, Germany, have 5 invented certain new and useful Improvements in Fuses and Adjusting-Keys Therefor, of which the following is a specification.

The present invention relates to fuses and 10 adjusting keys therefor and is an improvement on the fuse and adjusting key forming the subject matter of the copending application of Friedrich Ziegenfuss, filed Oct. 7, 1907, Serial Number 396345.

15 In the accompanying drawings Figure 1 shows the adjusting key in section, the fuse being shown in dotted lines; Fig. 2 is a top view of the key, partly in section and Fig. 3 is a side view of the fuse, partly in section. 20 The main difference between the adjusting key according to the present invention and the key of the aforesaid application consists in the arrangement and formation of the bolt M which in its securing position 25 prevents the adjusting key being lifted off the fuse. The annular body A of the adjusting key is provided with an arm A¹ and contains a ring B which can rotate in the body A but is held from axial displacement 30 therein. The ring B can be adjusted relatively to the body A through the medium of a worm C which is journaled in the body A and which meshes with the toothed periphery b¹ of the ring. In the ring B is 35 swingingly arranged a spring-pressed latch b⁴ for which a notch d¹ is provided in the fuse base D. The body A is provided with a stud a⁴ which is diametrically opposite to the arm A¹ and which fits in a notch e¹ pro-

40 vided in the rotatable composition ring E of the fuse. The latch b⁴ and the corresponding notch d¹ and also the stud a⁴ and the corresponding notch e¹ are formed in such a manner that the latch b⁴ and the stud a⁴ can 45 pass out of engagement with the corresponding notch d¹ and e¹ when the adjusting key is withdrawn from the fuse.

The relatively wide bolt M is provided 50 with a projection or edge m¹ which projects forwardly from the front face of the key and the bolt is mounted in the body A of the key in such a manner that the projection m¹ is adapted to slide in a circumferential groove k¹ (Fig. 3) in the fuse while 55 the fuse is being adjusted. The groove k¹

is formed through the enlargement of the joint k² between the rotatable composition ring E and the fixed composition ring K of the fuse. In order to make it possible to arrange the bolt M in the aforesaid manner 60 in the key-body A the key-body is of such height that, when the key is placed on the fuse, the key-body surrounds not only the rotatable composition ring E but also the lower part of the fixed composition ring K. 65 As in the key of the aforesaid application the arrangement of the bolt M is furthermore selected in such a manner that the bolt can move in a direction radial to the axis of the body A and is located diametrically 70 opposite to the nose a⁴, as already explained. The seat a² in the key-body A which serves to receive the bolt M is open at the top and is covered by a plate N which holds the bolt on its seat. The bolt has a projection m² 75 which serves as a handle and projects through an opening n¹ (Fig. 1) in the plate N. The walls n² and n³ of the opening n¹ limit the movement of the bolt. The bolt is further provided with a projection m³ which 80 projects into a recess a³ in the arm A¹ of the key-body and abuts against a spring m⁴ arranged in the recess a³, the recess being covered by the plate N. The spring m⁴ tends to hold the bolt in its securing position. 85 The arm A¹ of the body A is provided with a handle L.

After the key has been adjusted, it is placed upon the fuse in such a position that the nose a⁴ engages with the notch e¹. When 90 this takes place, the bolt N is forced back into its bearing and then the projection m¹ of the bolt M under the action of the spring m⁴ comes into engagement with the groove k¹. In this position the adjusting key is 95 secured from being lifted off the fuse. After the adjusting key has been placed on the fuse the key is turned by means of the handle L in the direction of the arrow x (Fig. 2) until the latch b⁴ enters the notch d¹ in 100 the fuse base D. The desired adjustment has been imparted to the fuse and no more turning is possible. During the turning of the key the projection m¹ of the bolt M slides in the groove k¹. After the fuse has been adjusted the bolt is, by means of the handle m², 105 moved toward the handle L to such an extent that the handle m² hits the wall n³ of the opening n¹ in the plate N, whereby the projection m¹ of the bolt M is withdrawn from 110

the groove k^1 and the adjusting key can then be lifted off the fuse.

The advantage of the improved adjusting key over the key of the aforesaid application consists in the fact that the notch which is provided for the bolt, in the composition ring, can be done away with.

Having thus described the invention, what is claimed and desired to be secured by Letters Patent is:—

1. An adjusting key for fuses comprising setting members and means for coupling said members with the fixed and movable parts respectively of a fuse, and a retaining device for the adjusting key independent of said coupling means and adapted to engage within a circumferential groove of the fuse and hold the setting key against displacement from the fuse.
2. An adjusting key for fuses comprising setting members and means for coupling said members with the fixed and movable parts respectively of a fuse, a retaining device for the adjusting key independent of said coupling means and adapted to engage within a circumferential groove of the fuse and hold said setting key against displacement from the fuse, and a member on the retaining device through which it is removed from engaging position.
3. An adjusting key for fuses comprising an annular setting member provided with a means for coupling it with the adjustable fuse part, and a manually releasable bolt adapted to engage a circumferential groove of the fuse and having a permanently fixed angular distance from said coupling means for preventing the key being lifted off the fuse.
4. An adjusting key for fuses comprising an annular setting member provided with a means for coupling it with the adjustable fuse part, and a manually releasable bolt situated permanently opposite to said coupling means and adapted to engage a circumferential groove of the fuse for preventing the key being lifted off the fuse.
5. An adjusting key for fuses comprising an annular setting member provided with a means for coupling it with the adjustable fuse part, and a manually releasable bolt adapted to engage a circumferential groove between the fixed and adjustable fuse part and having a permanently fixed angular distance from said coupling means for preventing the key being lifted off the fuse.

6. In an adjusting key for fuses, the combination with an annular body portion adapted to girdle a projectile and provided with a nose for engaging an adjustable fuse ring of the projectile; a ring rotatably mounted in said annular body and provided with means for rotating it relatively to said body to set it, said rotatable ring being provided with a nose for engaging the stationary fuse ring; a radial arm projecting from the upper portion of said annular body; and a radially sliding bolt in said arm, said bolt being adapted to releasably engage a groove on the fuse.

7. An adjusting key for fuses, having an arm, and a securing means for said key, said means comprising a bolt mounted to have sliding movement within a recess in the upper surface of said arm and adapted to releasably engage in a groove on the fuse of the projectile, said bolt having a member projecting therefrom in convenient position to be engaged by the hand of the operator.

8. An adjusting key for fuses, having an arm and a securing means for said key, said means comprising a bolt mounted to have sliding movement within a groove in the upper face of said arm and adapted to engage within the fuse rings of a projectile, a plate on said arm overlying the groove and keeping the bolt in position, and a member on said bolt projecting through the plate into convenient position for engagement by the hand of the operator.

9. In an adjusting key for fuses, the combination with an annular member adapted to engage an adjustable fuse ring of a projectile, a ring rotatably carried by said member, said ring being adapted to engage a stationary fuse ring of the projectile, and a radially disposed bolt mounted to have sliding movement within a groove in the upper face of said member, and a plate overlying said bolt and having a perforation, an upwardly disposed member projecting through said perforation and into convenient position for gripping by the hand of the operator, said bolt being adapted to releasably engage in a groove in said projectile.

The foregoing specification signed at Dusseldorf, Germany, this 15th day of February, 1908.

ULRICH WILCK.

In presence of—

WILHELM FLASCHE,
PETER LIEBER.
